UNITED STATES PATENT OFFICE.

LOUIS CARROLL STUKENBORG, OF CHICAGO, ILLINOIS, ASSIGNOR, BY MESNE ASSIGNMENTS, TO STUKENBORG CORPORATION, OF WILMINGTON, DELAWARE, A CORPORATION OF DELAWARE.

COTTON PICKER.

Application filed June 25, 1918. Serial No. 241,745.

To all whom it may concern:

Be it known that I, LOUIS CARROLL STUKENBORG, a citizen of the United States, and a resident of Chicago, in the county of Cook 5 and State of Illinois, have invented certain new and useful Improvements in Cotton Pickers; and I do hereby declare that the following is a full, clear, and exact description thereof, reference being had to the accompanying drawings, and to the characters of reference marked thereon, which form a part of this specification.

This invention relates to improvements in cotton picking machines, and refers, in 15 its general aspects, to that type of cotton picking machine illustrated in my prior application for U. S. Letters Patent, Serial No. 211,176, filed January 10, 1918, and also shown in my prior U. S. Letters Patent No. 20 1,264,575, granted on the 30th day of April, 1918. Certain of the improvements referred to herein, however, may be applied to cotton picking machines differing specifically from the constructions shown in the afore- 25 said application and patent.

Among the objects of the present invention is to provide a novel means for separating the dirt and other extraneous matter from the cotton staple after it has been removed from the bur.

A further object of the invention is to 30 provide novel picking means, embracing brushes or analogous elements having co-acting rows of bristles which directly engage the seed cotton to remove them from the burrs; and in this respect said improvements relate in part specifically to rows of bristles alternately long and short, for an improved operation hereinafter to be set 35 forth.

Another object of the invention is to 40 provide novel means of mounting the picker brushes in the head, whereby they may be readily removed from and placed in position when the parts of the picker head casting are separated.

Another object of the invention is to 45 provide a novel form of take-off device for removing the cotton staple from the picker means, and for delivering it into the area

of the rearwardly moving blast of air that carries the staple from the head backwardly through the conveying tube to the basket or other receiving device on the machine frame.

A further object of the invention is to 55 provide novel means for mounting the take-off device in the picker head so as to enable the take-off device, as a whole, to be readily removed from the head when the members 60 constituting the head are separated.

A further object of the invention is to 65 simplify the gear connection between the driving shaft of the motor to the take-off device and picker means so as to substantially lighten the head and reduce friction in the driving means, and so, also, to permit ready detachment of the transmission shaft from the picker and take-off devices, and to thereby enable the head to be detached from 70 the transmission shaft.

Another object of the invention is to 75 provide simple and easily manipulatable means for removing the picker head from the conveying tube and detaching said head from the driving means.

A further object of the invention is to 80 provide means for removing the burrs from the cotton plant so that unopened or imperfectly opened burrs, together with the cotton bolls, may be detached from the plant and passed through the head, and thereby enable such unopened or imperfectly opened burrs and enclosed seed cotton to be operated upon in a manner to break the burrs 85 from the seed cotton and to permit the burrs to be removed from the seed cotton, whereby the cotton staple and seed, heretofore largely left in the field, may be reclaimed for use.

Another object of the invention is to 90 provide novel means, in connection with a picker device of this character, by which unopened burs may be readily opened for access of the picker means to the seed cotton.

Another object of the invention is to 95 provide a novel means for counter-balancing the weight of the picker head conveying tube and transmission shaft.

Other objects of the invention are to improve and simplify cotton picking machines,

and the invention consists in the combination and arrangement of the parts shown in the drawings and described in the specifications, and is pointed out in the appended 5 claims.

In the drawings,—

Figure 1 is a side elevation, partially in section, of a cotton picking machine embodying my invention.

10 Figure 2 is a top plan view of the picker head, with parts in section.

Figure 3 is a longitudinal section, partially in elevation, on the line 3—3 of Figure 2.

15 Figure 4 is a detail section on the line 4—4 of Figure 3.

Figure 5 is a detail side elevation, illustrating the manner of non-rotatively supporting the take-off device in the picker 20 head frame.

Figure 6 is a section, partially in elevation, on the line 6—6 of Figure 3.

Figure 7 is a section on the indirect line 7—7 of Figure 3.

25 Figure 8 is a front elevation of the picker head showing a modification.

Figure 9 is a sectional view of a take-off device showing a modified means of connecting the take-off fingers to the inner 30 sleeve of the take-off device.

Figure 10 is a section on the line 10—10 of Figure 9.

Figure 11 is a partial elevation and partial sectional view of another form of take- 35 off device.

As shown in the drawings, 10 designates the frame of the machine which has the general form of a truck, supported on two rear wheels 11 and on a bracket 14. The frame 40 comprises suitably fabricated and connected metal bars with screen-like or foraminated enclosing walls 15. The frame may be moved from place to place manually by a hand bar 16 attached to the forward end of 45 the frame. So far as the details of the frame structure are concerned, however, it is understood that it may assume other forms and in some instances may have the form of a motor driven truck.

50 17 designates a basket supported on the rear end of the frame to receive the cotton. It comprises suitably shaped fabricated metal bars 18 between which are stretched foraminated or screen-like walls 19. It is 55 removably or detachably supported on the frame 10 by means of hooks 20.

21 designates a blower that is supported on the frame and its induction side is connected, through the medium of a conveying 60 tube 22, with the picker head 23. To the induction side of said blower is connected a discharge pipe 24 that discharges the picked cotton into the basket at a point near the top thereof. Said blower is driven by a 65 motor, which may be an explosion engine

25 mounted on the frame, the connections herein shown being a belt 26 that is trained about a driving pulley on the motor and a driving pinion on the shaft of the blower 21.

The motor 25 also drives, through a belt 70 or other transmission 27, a countershaft 28 that is mounted in bearings 29, 29 carried by the frame, and through said countershaft, a flexible or jointed transmission shaft comprising sections 30, 30, the casings of which are flexibly connected by known forms of hinged joints 31, and the shaft sections of which are connected at said joints by meshing gears 32 familiar in this form of driving shaft.

75 The terminal section 33 of said transmission shaft is rotatively mounted in its casing section 34 which, in turn, is loosely supported in a bushing 35 that is mounted in a neck or extension 36 of the picker head 23.

80 The casing of the picker head is herein shown, and preferably, as made of two like shaped lateral members 38, 39 that are joined by bolts or screws 40 extending through mating lugs on the margins thereof. The neck or extension 36 to receive and support the terminal member of the transmission shaft is preferably made an integral part of the casing, and comprises two halves or parts that are mated to constitute the completed neck and are held together by the screws or bolts 40. Said head 85 comprises an enlarged mouth 41 that is open at the front of the head, as indicated in Figures 4 and 6, and a neck 42 to which the conveying tube is connected.

85 The weight of the picker head, conveying tube, and transmission shaft is counterbalanced by a counterweight 45 which is connected, through a strand or cable 46, with the inner section 30 of the transmission shaft at a point near the upper end of said section. Said cable is trained over a pulley 47 that is carried by a bracket 48 which is mounted on and extends above a support 49 that is connected in any suitable manner at its lower end to the frame or truck. Preferably and as herein shown, 100 said support 49 is tubular to receive and guide the weight 45.

105 Said counter-weight serves, in the manner referred to in my aforesaid application for United States Letters Patent, to counter-balance the weight of said parts and also to avoid side whipping of the transmission shaft.

110 The picker mechanism embraces in its construction two rotative brushes comprising cores 50, 50 and angularly spaced rows of bristle tufts 51, 52. In accordance with the present invention, alternate rows of tufts, the rows 51 as herein shown, are made shorter than the other rows. In accordance with a further feature of the in- 115

vention the said tufts are so relatively spaced that they are brought into endwise contact at the meeting sides of the brushes instead of the rows of bristles of one brush 5 passing into the spaces between the rows on the other brushes.

The result of making the bristles of alternate long and short rows is that the longer bristles reach out the required distance for 10 contact with the seed cotton, while the shorter bristles, being stiffer, are effective to efficiently pull the cotton between the brushes. In making said longer bristles of a length to thus effectively reach into the 15 burrs for contact with the seed cotton, said bristles become more flexible than desired and their pulling force is somewhat reduced by reason of this flexibility. The shorter bristles, on the other hand, can be made sufficiently stiff to be very effective in grasping the cotton and drawing the same between the brushes.

The result of spacing the rows of bristles so that they will endwise mesh at the proximate 25 sides of the brushes is to effect a firmer grasp on the cotton by the shorter bristles, as will be apparent from an inspection of Figure 3.

The brush shafts 55 are mounted in anti-friction bearings 56 contained, as herein shown, in hollow bosses 57 of the casing walls; and the cores of the brushes are also provided with extended shells 58 which overlap the bearing bosses to prevent cotton 35 wrapping about said bearings.

In accordance with another feature of the present invention, the brush cores are removably mounted on their shafts 55 so that the cores, with the bristles, may be 40 moved endwise from and in like manner placed on said shafts when the two members 38, 39 of the picker head casing are separated. This arrangement is shown as effected in the present instance by making 45 the intermediate portions of the shafts of square cross section and similarly fashioning the axial openings in the brush cores to receive them; the fit being a close fit but permitting the brush cores to be readily 50 removed endwise from and placed on the shafts.

Any other kind of interlocking connection, suitable for quick detachment and replacement, may, however, be employed.

Located in rear of the picker brushes is a take-off device designated as a whole by 60. As in the construction shown in my aforesaid application, said take-off device embraces a shell 61 that has at its ends interior cylindric bearings 62 which are rotatively mounted on exterior cylindric bearings of supporting blocks 63 that are carried by the side walls of the casings. Said shell is perforated for the passage of 65 pins or fingers 65 that are set at their inner

ends in grooves 66 of a sleeve 67 that is mounted on and rotates with a shaft 68 which extends transversely across the casing and is mounted at its ends in bearings formed in the blocks 63. The said pins 65 are loosely fixed to the sleeve 67 by means of short pins 70 that are extended through longitudinal openings in the sleeve which intersect the grooves 66, and extend also through apertures in the inner ends of the pins within said grooves. The pins 70 are held in place by means of discs 72 which are fitted closely over the shaft 68 and have short tubular flanges 73 which fit closely on the shaft and said discs bear against the 80 ends of the sleeve and pins.

Two driving pins 65' are fixed to and turn with the sleeve 67 and shaft 68 and extend through openings in the shell to transmit motion to the shell to turn it and its bearings. Preferably, also the shell 61 is provided in the planes of the openings which receive the pins 65 with internal grooves to facilitate the work of enlarging the inner 85 ends of said openings to permit free movement of the pins.

In accordance with another feature of the present invention, the said take-off device is removably mounted in the picker head casing so as to be readily removed therefrom when the two members of the casing are parted. To this end the blocks 63 are provided with squared projections 74 through which shaft 68 extends, and the casing sections or parts are provided at their 90 meeting edges and at opposite sides of the plane in which said edges meet with matching recesses 75, 75. It will thus be seen that when one section of the casing is removed from the other, the take-off device 95 may be laterally removed from the casing. This feature of the device is advantageous in that it affords means for readily removing the take-off device for the purpose of 100 repairing or replacing the same.

The take-off device shaft 68 is extended upwardly beyond its bearing in the block 63 to provide an extension 75' that is contained in a chambered portion 38' of the casing at the base of the neck 36. Said extension shaft, in accordance with another feature of the present invention, is adapted to be connected to the terminal section 33 of the transmission shaft through some suitable form of detachable connection or joint. As herein shown, the inner end of the terminal shaft section is formed with a socket 77 to receive the outer end of the shaft extension 75'. Said inner end of the terminal section 33 is also provided at said socket with diametrically opposed slits 78 (Figures 3 and 7) to receive a cross pin or bar 79 on the shaft extension 75'. The said cross pin or bar 79 interlocks with the slotted portion terminal section of the trans-

mission shaft to provide a reliable driving connection between the parts, and also permits the terminal section of the transmission shaft to be readily detached from the 5 shaft extension 75'.

In order to prevent the connected shaft sections from parting during the operation of the machine, the said socketed end of the shaft is enlarged to provide a shoulder 81 10 that bears against the inner ends of the casing 34 and bushing 35; and a clamping ring or strap 82 is applied to the outer end of the neck 36 to clamp the two members of the neck closely on the bushing 35. By releasing 15 the clamping screw 83, which holds the clamping ring or strap in place, the bushing 35, the casing 34, and shaft section 33, are free to be removed endwise from the neck 37.

20 In connection with the detachable driving joint thus described, means are provided for permitting the conveying tube to be readily removed from the neck 42 of the picker head casing. This may be effected by inserting 25 a metal or like sleeve 85 in the outer end of the conveyor tube 22 and slipping said sleeve 85 over the end of the picker head casing neck. In order to prevent too ready detachment of the parts, the said sleeve may be 30 formed with a spring tongue 88 which is provided with a holding dog 89 to engage in a socket 90 of the neck.

The provision of the detachable connections between the conveyor tube and head 35 and also between the transmission shaft and the mechanism within the head permits the head to be readily removed from the machine, which it is desirable to do when leaving the machine in the field or other place 40 where the head may be exposed to the elements or may be maliciously removed.

The brush shafts are geared to the shaft 68 in a simple manner through the medium of a beveled pinion 92 fixed to said shaft 68 45 and meshing with a beveled wheel 93 that is fixed to the inner end of a short shaft 94 rotatively mounted in a bearing 95 carried by the adjacent side of the head. To the outer end of said shaft is fixed a spur wheel 50 96 that meshes with one of a pair of meshing spur wheels 97, 97 that are fixed to and drives the brush shafts. The said spur wheels 96, 97 are protected by a removable casing or hood 98 fastened to one side of the 55 casing.

The head is provided in one side wall of the casing and abreast the take-off device, with an air receiving opening 100, through 60 which the major portion of the air, set in motion by the fan 21, is drawn into the head in the same manner as set forth by my prior application and patent, a small fraction of the air entering the head through the mouth 41. The air so set in motion backwardly 65 through the head and tube carries the cot-

ton to the receiving basket 19. The picker brushes and take-off device act in the manner set forth in my aforesaid application and patent to comb or open the cotton staple and to thereby release boll dirt and other 70 extraneous matters from the cotton staple. The air entering the head, through the action of the fan 21, carries the staple and boll dirt backwardly through the conveying tube and the boll dirt and other extraneous 75 matter, being somewhat heavier than the cotton staple, is carried in advance of the latter. Therefore, when the cotton staple and boll dirt passes into the receiving basket the boll dirt is freed from and slightly in 80 advance of the staple so that it passes directly through the screen-like or foraminated wall of the basket, as indicated in Figure 1, so as to separate the boll dirt and like objectionable matter from the cotton; the 85 clean, loose cotton falling into the bottom of the basket. In this manner the cotton is not only opened or loosened and prepared as a better ginning product but is also delivered to the basket practically free of boll 90 dirt and the like.

In Figure 8 is shown an arrangement whereby unopened or imperfectly opened burs may be detached from the plant and both the burs and seed cotton carried 95 through the picker mechanism and the burs broken from the seed cotton so that the burs may be readily separated from the resulting cotton staple by merely picking the broken burs from the staple. It has been found 100 that the brushes and take-off device are sufficiently strong, especially when using the alternate shorter bristles, to effectively break the burs of this kind of cotton so that the product delivered back to the receiving 105 basket consists of the cotton staple mixed with the broken pieces of burs. Heretofore it has been the practice when handling cotton of this character to pick or detach the bur and closed seed cotton from the plant by 110 hand, and afterwards break the burs from the seed cotton by hand and separate them from the staple. Owing to the labor cost of doing this work, cotton of this character has largely remained in the field as a waste 115 product. The value of this character of cotton lies chiefly in the cotton seed which may be taken therefrom, although the cotton staple itself has a given value as a low standard 120 staple. With the present arrangement, now to be described, it becomes practical to detach the burs from the plant and remove them from the staple at a small cost of labor.

One practical means of effecting this result is to provide at one side of the mouth 125 a knife blade 105 which is provided between its ends and near the proximate sides of the brushes with a V-shaped notch 106, the sides of which are formed to provide cutting edges 107. When this construction is em- 130

ployed, the guards 108 shown in Figures 3 and 4, and which are used in the construction before described in the same manner and for the same purpose as in my prior application and patent, are omitted. In using the modified construction shown in Figure 8, the bur is grasped and the knife edges are brought to bear on the stem in rear of the bur to sever the stem from the plant. The 10 brushes directly engage and carry the bur and enclosed seed cotton into the head, and by reason of the compression of the bur as it passes between the brushes and by reason of its engagement with the take-off device, 15 said bur is broken up into fragments and carried back as such fragments along with the cotton staple.

It will be understood, however, that any other suitable means of breaking up the burs 20 may be employed, as, for instance, a breaking device consisting of two wire, or other stiff, interacting brushes and used with or without a take-off device.

In the present construction and where the 25 guards 108 are used, they are attached to the casing walls above and below the brushes in a manner specifically different than shown in my prior application and patent. As herein shown, the upper and lower casing wall of 30 the mouth is provided with shallow notches 110, through which the guards extend, and the guards are anchored to the head by means of anchor bars 111 that are detachably fixed to the head in any suitable manner. The guards herein shown are U-shaped, 35 the same as illustrated in my aforesaid patent, and one member of each U-shaped guard is made shorter than the other and is normally separated from its anchor bar 111, so 40 that, when the guards are pressed inwardly by the force of the brushes in pulling the cotton, the shorter ends of the U-shaped guards constitute stops to limit movement thereof towards the brushes.

45 In Figures 9 and 10 is shown a modified form of take-off device relating more specifically to the manner of loosely connecting the take-off pins or fingers with the inner eccentric sleeve. As shown in said drawings, 118 50 designates the take-off drive shaft corresponding to the shaft 68 above referred to. 119 designates the sleeve mounted thereon, 120 designates the perforated shell disposed eccentric to the sleeve 119 and rotatively 55 mounted on the bearing blocks 121 that correspond to the bearing blocks 63 above referred to, and 122 designates the take-off pins or fingers which are movable through the perforations of the shell 120. In this 60 construction the sleeve 119 comprises an intermediate or central portion and two end portions 119', 119''. The proximate faces of each end of the sleeve 119 and the adjacent sleeve portion 119' are formed with semi- 65 spherical recesses 123, 124, respectively. The

recesses 123 and 124 when opposed in matching relation constitute sockets to receive enlargements or balls 125 formed on the inner ends of the pins 122. The construction described constitutes a ball and socket connection between the inner sleeve 119 and the pins 122. The opposed end faces of the intermediate and end sleeve sections or parts are cut away or properly spaced to permit the required angular movement of the pins 75 relatively to the sleeve.

The take-off device shown in Figure 11 comprises a shell 130 that is rotatably mounted on the bearing blocks 131, 131, the latter corresponding to the blocks 63 of the 80 first described construction. 132, 132 designate the take-off pins or fingers which extend through the perforations of the shell 130, and 133, 133 designate the locking or driving pins which also operate through the 85 openings in the shell. Said pins extend through openings in the finger mounting sleeve and into the shaft 134, corresponding to the shell 68 of the first described construction.

The finger mounting sleeve surrounding the shaft 134 in this instance is made of three members, an intermediate member 135 and end members 136. The inner ends of the fingers 132 are provided with inwardly turned bearing studs 138, giving to said fingers a general L shape, and said studs are seated in sockets 139 that are disposed longitudinally of the intermediate sleeve sections 135, and they are located just inside the ends of the latter. The said fingers are held in place with their studs seated in said sockets 139 by the end sleeve sections 136.

With this construction, the pins may be readily removed from the intermediate sleeve section 135 after the end sleeve sections 136 have been shifted endwise of the shaft 134.

In other respects this hereinbefore specifically referred to construction and operation of the mechanism is substantially the same as that shown in my prior United States patent and application.

It is to be understood that the details of the construction herein illustrated, which have been particularly described, may be varied within the spirit and scope of the present invention and that said invention is not limited to such details except as to claims here specifically set forth and as imposed by the prior art.

I claim as my invention:—

1. A cotton picker comprising a manually manipulated head, interacting picker and fibre loosening mechanism therein, constructed to comb and loosen the cotton locks, to segregate them and their adhering seeds from each other and loosen boll dirt therefrom to produce a fluffy seed cotton, said mechanism including oppositely disposed,

coacting, rotative, picker means arranged to rotate rearwardly at their coacting sides, a foraminated element, and pneumatic means connected to the head to carry the cotton 5 rearwardly from the head constructed to deliver the cotton and loosened boll dirt against said foraminated element.

2. In a cotton picker, a picker head, interacting brushes mounted therein to rotate 10 in opposite directions and provided with angularly spaced rows of bristles, the bristles in certain rows of each brush being shorter than the bristles of the other rows of said brush.

15 3. In a cotton picker, a picker head, interacting brushes mounted therein to rotate in opposite directions and provided with angularly spaced rows of bristles, the rows of bristles of the two brushes being angularly 20 spaced to meet in endwise meshing engagement, and the bristles of alternate rows of each being shorter than those of the other rows thereof, and means to remove the cotton from the brushes.

25 4. In a cotton picker, a picker head, interacting brushes mounted therein to rotate in opposite directions and provided with angularly spaced rows of bristles, the bristles of certain rows of each brush being shorter 30 than the bristles of the other rows of said brush, and a take-off device in rear, of and rotative in contact with said brushes.

35 5. In a cotton picker, a picker head comprising separable members formed at one end to provide a forwardly open mouth and provided at its other end with an outlet in line with a suction conveying tube, coacting rotative picker brushes at said mouth whose axes of rotation are transverse to the plane 40 of separation of said members, and brush shafts rotatively mounted in bearings in the walls of the said separable members, and movable endwise from said bearings, whereby when said members are separated, corresponding ends of the shafts may be removed 45 endwise from their bearings.

50 6. In a cotton picker, a picker head, embracing separable members and having an open mouth, interacting, rotative picker brushes at said mouth, said brushes embracing cores having axial openings, and shafts extending through and endwise removable from, but rotatively locked in said axial openings, said casing members being separable in a plane permitting the shafts and brushes to be bodily removed endwise from 55 said members when the latter are separated.

60 7. In a cotton picker, a picker head embracing a two part casing and provided with an open mouth, rotative, interacting picker brushes at said mouth, shafts rotatively mounted in bearings carried by opposing walls of said casing and having portions interlocked to the brushes by means permitting 65 the brushes to be removed endwise there-

from, said shafts and the axes of the brush cores lying in planes at right angles to the plane in which the casing members meet.

8. In a cotton picker, a picker head embracing interacting brushes, and a take-off device in rear of and coacting with said brushes, comprising a perforated shell, fixed supporting members on which said shell is rotatively mounted, an inner, rotative member eccentric to the axis of the shell, pins 70 movable through the perforations of said shell, and ball and socket connections between said pins and said inner member.

9. In a cotton picker, a picker head embracing interacting picker means, a take-off 80 in rear of and coacting with the picker means comprising a perforated shell, bearings on which said shell rotates, a rotative member within and eccentric to the axis of said shell comprising separable intermediate 85 and end portions, said end portions and intermediate portions being formed on their proximate faces to provide recesses, and take-off pins movable through the perforations of the shell and having end portions 90 to loosely engage said recesses.

10. In a cotton picker, a picker head embracing interacting picker means, a take-off device in rear of and coacting with said picker means embracing fixed bearing blocks, 95 a perforated shell rotatively mounted thereon, a rotative sleeve within an eccentric to said shell embracing separable intermediate portion and two end portions, a driving shaft extending through said sleeve portions, 100 to which the end sleeve portions are threaded, said end portions and the intermediate portion of the sleeve being formed to provide recesses, and said end portions bearing against said bearing blocks, and take-off fingers movable through the apertures of the shell and having inner end portions to loosely engage said recesses.

11. In a cotton picker, a two part separable casing, interacting picker means therein, a take-off device rotatively mounted in the casing in rear of the picker means, and bearings for the take-off device interlocked to the casing wall at the plane of separation of the two part casing.

12. In a cotton picker, a picker head embracing two casing members which meet at their edges to constitute a picker head casing, and formed to provide an open mouth and a rearwardly extending neck, rotative, interacting picker means at said mouth, and a rotative take-off device in rear of the picker means embracing bearing blocks that are detachably interlocked to the casing members at their meeting edges by means which permit ready separation of the blocks from the casing when the casing members are separated.

13. In a cotton picker, a picker head casing comprising two shell-like members, the 130

- edges of which meet in abutting relation, said casing formed with an open mouth, interacting picker means at said mouth, and a rotative take-off device in rear of the 5 picker means embracing bearing blocks having angular cross section extensions, the casing members being provided at their meeting edges with notches to interlockingly receive said extensions.
- 10 14. In a cotton picker, a picker head comprising a two-part shell, the members of which abut at their edges, said casing being formed to provide an open mouth, interacting picker means at said mouth, the 15 casing members being formed in rear of said picker means with mating recesses to form notches in opposing walls of the head, a rotative take-off device in rear of the picker means, and bearing members for said 20 take-off device having extensions removably seated in said notches.
- 15 15. In a cotton picker, a picker head comprising a two-part shell, the members of which abut at their edges, said casing being 25 formed to provide an open mouth and formed in rear of said picker means with mating recesses to provide notches in opposing walls of the head, interacting picker means at said mouth, a rotative take-off device in rear of the picker means, bearing 30 members for said take-off device having extensions removably seated in said notches, and a shaft rotatively mounted in said bearing members and extending through the 35 extensions thereof, with means to rotate said shaft.
- 16 16. In a cotton picker, the combination with a casing formed to provide an open 40 mouth and a shaft bearing neck, of interacting, rotative picker brushes at said mouth, a rotative take-off device in rear of the picker brushes, a shaft rotatively mounted in the head for driving said take-off device, a transmission shaft section rotatively 45 mounted in said neck, and means to directly connect said shaft section with the take-off device shaft.
- 17 17. In a cotton picker, the combination with a casing formed to provide an open mouth and a shaft bearing neck, of interacting, rotative picker brushes at said mouth, a rotative take-off device in rear of the picker brushes, a shaft rotatively mounted in the head for driving said take-off device, a 50 transmission shaft section rotatively mounted in said neck, means to directly connect said shaft section with the take-off device shaft, and operative gear connections between said take-off device drive shaft and said picker brushes to drive the latter.
- 18 18. In a cotton picker, the combination with a casing formed to provide an open mouth and a shaft bearing neck, rotative, interacting picker brushes at said mouth, a 55 rotative take-off device in rear of the picker
- brushes, a shaft rotatively mounted in the head for driving said take-off device, a transmission shaft section rotatively mounted in said neck, said take-off device driving shaft provided with a shaft extension, and an endwise detachable, interlocking connection between said shaft extension and said transmission shaft section. 70
- 19 19. In a cotton picker, the combination with a casing formed to provide an open mouth and a shaft bearing neck, rotative, interacting picker brushes at said mouth, a rotative take-off device in rear of the picker brushes, a shaft rotatively mounted in the head for driving said take-off device, a transmission shaft section rotatively mounted in said neck, said take-off device driving shaft provided with a shaft extension, an endwise detachable interlocking connection 75 between said shaft extension and said transmission shaft section, and means for locking the transmission shaft section in the neck while permitting it to be removed endwise therefrom to detach it from said shaft extension. 80
- 20 20. In a cotton picker, the combination with a casing formed to provide an open mouth and a shaft bearing neck, of interacting, rotative picker brushes at said mouth, a rotative take-off device in rear of the picker brushes, a shaft rotatively mounted in the head for driving said take-off device, a transmission terminal shaft section 85 rotatively mounted in said neck, the terminal transmission shaft section being fitted to rotate in said neck and to be endwise removed therefrom, and provided at its inner end with a socket to fit over said take-off device shaft, and interlocking means between said transmission terminal shaft section and said take-off device shaft. 90
- 21 21. In a cotton picker, a picker head embracing two shell-like members abutting at their edges and formed to provide an open mouth and also a two-part shaft bearing 95 neck, rotative, interacting picker brushes at said mouth, a rotative take-off device mounted in the head in rear of said brushes, a shaft for driving said take-off device, a bearing bushing in said two-part neck, a terminal transmission shaft section rotatively mounted within said bushing, a joint 100 interlockingly connecting said terminal section and take-off device shaft by means permitting endwise separation thereof, said terminal section having a shoulder to engage the inner end of said bushing to prevent endwise withdrawal of the terminal section, and means to clamp the two part neck 105 against said bushing. 110
- 22 22. In a cotton picker, a picker head embracing a casing shaped to provide an open mouth, rotative, interacting picker brushes at said mouth provided with shafts which are mounted in the casing walls, a rotative 115

- take-off device mounted in rear of the picker brushes, a shaft rotatively mounted in the casing walls for driving said take-off device, a transmission shaft having a terminal section that is mounted in said casing and is directly connected to said take-off device shaft by means permitting endwise separation therefrom, a bevel pinion on said take-off device shaft, a counter-shaft having 5 a beveled wheel meshing with said pinion, and operative connections between said counter-shaft and said brush shafts.
23. In a cotton picker, the combination with a picker head comprising a casing having an open mouth, and a rearwardly directed discharge neck, interacting picker means at said mouth, and pneumatic means for carrying the cotton rearwardly from the picker means embracing a conveyor tube, a member fitted to said tube and adapted to telescope over the rear end of said discharge neck, and a resilient tongue on said member formed with a projection adapted to detachably engage a socket in said discharge neck.
24. In a cotton picker, the combination with a picker head formed with an open mouth and with a rearwardly directed discharge neck, interacting picker means at 30 said mouth, a rotative take-off device in rear of the picker means, and a driving shaft for said take-off device, of a transmission shaft having bearing in said head, means to detachably connect said transmission shaft to said take-off device driving shaft, operative driving connections between said take-off device shaft and said picker means, pneumatic means for carrying the cotton rearwardly from the take-off device embracing a conveyor tube, and means for detachably connecting the conveyor tube to said neck. 40
25. In a cotton picker, a picker head comprising a casing having an open mouth, interacting picker means at said mouth, and a bar exterior to the head at one side of the mouth and provided with V-shaped cutting edges. 45
26. In a cotton picker, a picker head embracing a casing having an open mouth, interacting picker means at said mouth for engaging the cotton boll, and means carried by the head for opening unopened burs. 50
27. In a cotton picker, a picker head embracing a casing having an open mouth picker, interacting picker means at said mouth for engaging the bottom bolls, and a conical bur opening member extending laterally from the head at one side of said mouth. 55
28. A cotton picker comprising a suction device, a picker head, a conveying tube connecting the picker head and said suction device, a jointed shaft connected to the picker head and extending rearwardly therefrom, means to drive said shaft, a counter-weight, a cable connecting said weight to a section of said shaft near said driving means, a pulley over which the cable is trained and a support for said pulley in which the counter-weight is contained and 60 by which it is guided. 65
- In testimony whereof I claim the foregoing as my invention, I hereunto append my signature at Chicago, Illinois, this seventh day of June, 1918.
- LOUIS CARROLL STUKENBORG.
